United States Patent Office

Des. 183,506
Patented Sept. 16, 1958

183,506

TOY RATTLE

Robert Y. Allen and Melvin Shaw, Los Angeles, Calif.,
assignors to Plakie Toys, Inc., Youngstown, Ohio, a
corporation of Ohio

Application February 18, 1957, Serial No. 44,892

Term of patent 7 years

(Cl. D34—15)

Figure 1 is a front view of the toy rattle, showing our new design.

Figure 2 is a side view thereof; and

Figure 3 is a top view.

The back is substantially plain.

We claim:

The ornamental design for a toy rattle, as shown and described.
